CLAIM

The ornamental design for a glass oil lamp, as shown and described.

DESCRIPTION

FIG. 1 is a top perspective view of a glass oil lamp in accordance with my new design;

FIG. 2 is a right side elevational view thereof, the front, rear and left side elevations being identical thereto;

FIG. 3 is a top plan view thereof;

FIG. 4 is a bottom plan view thereof;

FIG. 5 is a top perspective view of an alternative embodiment of a glass oil lamp in accordance with my new design; and,

FIG. 6 is a right side elevational view thereof, the front, rear and left side elevations being identical thereto, and the top and bottom plan view being identical to the top and bottom plan views of the embodiment shown in FIGS. 1-4.

The broken lines are shown in FIG. 2 for illustrative purposes only and indicate the nature and use of my design. FIGS. 5 and 6 are broken away to indicate indeterminate length.
